(57) **CLAIM**

The ornamental design for a bumper assembly as shown and described.

DESCRIPTION

FIG. 1 is a perspective view showing a bumper assembly as seen from the top, front, and right side;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a reference view showing the bumper assembly in an exemplary environment.

The broken lines shown in the drawings represent unclaimed subject matter and form no part of the claimed design.

1 Claim, 5 Drawing Sheets
